ALEXANDER BOGDÁNFFY, OF NEW YORK, N. Y.

DISK-CUTTING MACHINE.

1,175,589.

Specification of Letters Patent. Patented Mar. 14, 1916.

Application filed December 15, 1914. Serial No. 877,412.

To all whom it may concern:

Be it known that I, ALEXANDER BOGDÁNFFY, a subject of the King of Hungary, and a resident of the city of New York, in the county of Kings and State of New York, have invented certain new and useful Improvements in Disk-Cutting Machines, of which the following is a specification.

The present invention relates to improvements in machines for cutting cork or similar disks for use in closures, such as for instance crown corks.

The invention pertains more particularly to a machine for cutting a cylinder or rod of cork or similar material into disks of a predetermined thickness.

One of the objects of the invention is to provide a machine of this type which is simple in construction, efficient in operation, and which reduces the waste to a possible minimum.

Another object of the invention is to produce a machine of the character specified wherein a single knife is used in conjunction with a plurality of cork holding magazines, in combination with a simple and positive feeding mechanism.

A still further object of the invention is to so arrange the elements of the machine to permit the thickness of the disks to be cut to be varied according to the requirements.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:

Figure 1 is a front elevation of a machine constructed in accordance with the present invention; Fig. 2 is a side elevation thereof; Fig. 3 is a plan view of the same; Fig. 4 is a plan view of a portion of the machine on a larger scale, partly in section; Fig. 5 is a plan view of a portion of the work table and the feeding mechanism, partly in sec-

tion; Fig. 6 is a section taken on line 6—6 of Fig. 5; Fig. 7 is a section taken on line 7—7 of Fig. 5; Fig. 7^a is a perspective view, partly in section, of a portion of the detail shown in Fig. 7; and Fig. 8 is a side elevation of a detail of construction.

Before going into the details of the machine, attention is called to the fact that, although in the drawings there have been shown two machines combined into one, that is to say two work supporting tables with two knives, it is obvious that the same could be built as a single machine, that is consisting of one work supporting table coöperating with one knife only.

Referring now to the drawings, the numeral 10 indicates the frame of the machine, including a horizontally disposed bed plate 11 on each side thereof. In each bed plate 11 are formed two longitudinally extending parallel guideways 12, in which are seated rails 13, which are formed upon the underfaces of work tables 14, there being one table disposed on each bed plate. The tables may be reciprocated upon the bed plates in any suitable manner, for instance the tables are each provided with a downwardly extending vertical plate member 15, which is rigidly attached thereto and provided each with a vertical slot 16. In each slot is slidably disposed a block 17, said blocks being formed upon crank disks 18, the latter being keyed or otherwise fixedly attached to the main driving shaft 19 of the machine, said driving shaft being rotatably mounted in bearings 20, which are formed upon the frame 10. Rotation is imparted to the driving shaft from any suitable source of power by a belt 21, that runs over a driving pulley 22, which is keyed to said shaft. The crank disks are keyed to the driving shaft in such a manner that, in the rotation of the latter, the work tables reciprocate always in opposite directions.

Upon each of the tables are disposed a plurality of rod holding magazines. For this purpose there are formed in the upper faces of the tables grooves 23, the bottoms of which are substantially semi-cylindrical. These grooves run throughout the widths of the tables in parallel relation to the main driving shaft. On each table these grooves are divided into two groups, one group, denoted by the numeral 24, being arranged near one end of the table, and the other group, designated by the numeral 25, near

the other end thereof. The purpose of this arrangement is, as will hereinafter appear, to make each table double acting, that is to say to run the machine without idle strokes. Along the inner edge of each table is formed a longitudinal ledge 26, in which are formed cylindrical bores 27 in alignment with and forming a continuation of the grooves 23. Each bore 27 is provided with an enlargement 28 for a purpose presently to be described. In each bore is slidably disposed a feeding finger 29 in the form of a spring collet, that is provided, besides the usual longitudinal slots 30, at its upper portion with a wider longitudinal slot 31, and in alignment with the latter at its lower portion with a similar slot 32. Into the slots 32 project strips 33, which are fixedly attached to the table, such strips serving, besides a purpose hereinafter to be described, to prevent a rotary motion of the feeding fingers in relation to the tables. The inner ends of the feeding fingers are somewhat thickened, as clearly shown at 34, these thickened portions being disposed in the enlarged sections of the bores, and each of the same being provided with an upwardly projecting vertical lug 35, said lugs being seated each in a slot 36, formed in actuating bars 37. There is one bar associated with each table. These bars are slidably disposed each in a groove 38, that runs throughout the corresponding ledge 26 in parallel relation to the longitudinal axis of the table. The slots 36 are arranged, as clearly appears in Fig. 4 of the drawings, at an angle to the longitudinal axis of the table, the slots associated with each group of grooves 23 being disposed parallel, and the longitudinal parallel axes of the two groups of slots converging toward the transverse center line of each table, or in other words the two groups of slots are inclined in opposite directions. With each actuating bar 37 co-operate two stops 39, one on each end of the bed plate 11. These stops comprise, for instance, each a standard 40, that is suitably fastened to the bed plate, and a horizontally disposed set screw 41 in the path of the bar 37. By adjusting the positions of the set screws 41, obviously the strokes of the bars 37 and thus the extent of the feed may be varied, as will hereinafter appear.

With each feeding finger co-operates a gripping jaw 42. These jaws are slidably disposed in pockets 43, formed in the ledges 26 on the tables. The jaws are provided with teeth 44 on their underfaces, said teeth projecting through the slots 31. These jaws co-operate with the strips 33, which are, as above described, seated in the slots 32 in the feeding fingers. Each gripping jaw is provided with a recess 45, in which is seated an eccentric 46, that is either made integral with or suitably attached to a rocking shaft

47. There is one shaft 47 associated with each table, the shafts being oscillatably mounted in the ledges 26, and provided each with a bevel gear 48. The bevel gear 48 of each shaft meshes with a similar gear 49, that is fixedly attached to a shaft 50, the latter being journaled in bearings 51 on the tables. The shafts 50 extend at right angles to the shafts 47, and carry at their outer ends each a lever 52. These levers carry each an anti-friction roller 53, said rollers being adapted to co-operate with cams 54. These cams are attached to the bed plate 11, one in front of the machine and the other in rear thereof. The cams have each two slanting faces 55 and 56, which converge toward the center line of the machine, as clearly shown in Fig. 1 of the drawings. The eccentrics 46 associated with the group 24 of grooves are all alike and in registering positions, and so are also those associated with the group 25 of grooves 23. It is to be noted, however, that the cams associated with the group 25 of grooves are staggered 90° in relation to the cams associated with the group 24 of grooves, as appears clearly from Fig. 8 of the drawings.

With each table co-operates a disk knife 57. These knives are rigidly attached to an arbor 58, that is mounted in bearings 59. Rotation is imparted to this arbor by a belt 60, that is actuated by any suitable source of power and runs over a pulley 61, keyed to said arbor. Below each knife is disposed a chute 62, into which the disks fall, to slide into containers placed below said chutes.

The operation of this machine is as follows: It is necessary to consider the operation of one table and its appurtenances only, since the other table works in a similar manner. Let us consider the operation of the table on the left-side of Fig. 3 of the drawings. The cork rods or cylinders 63 are placed into the grooves 23 manually, and slid in said grooves and feeding fingers until they are brought within the reach of the gripping jaws 42. In the positions of the parts shown in Figs. 1, 3 and 4 of the drawings, the grooves of the group 24 of the table have already passed the cutting edge of the knife. Immediately before the table reaches this position, the bar 37 is shifted by the corresponding stop 41 in the direction of the arrow shown in Fig. 4 of the drawings, whereby the feeding fingers associated with the group 24 move away from the knife, and the feeding fingers associated with the group 25 of grooves move in the opposite direction, for the reason that the slots 36, which co-operate with the lugs 35 on the feeding fingers, are, as above described, converging toward the transverse center line of the table. Before, however, the feeding fingers move in the directions indicated, the shaft 47 is given a rocking motion by the

lever 52, as the anti-friction roller 53 rides up the inclined surface 56 of the cam 54 before the bar 37 abuts against the corresponding stop 41. As this cam rides up this inclined surface, the lever 52 is moved in the direction of the arrow shown in Fig. 1 of the drawings, whereby the eccentrics 46 associated with the group 25 of grooves raise the gripping jaws 52, and the eccentrics associated with the group 24 of grooves lower the corresponding gripping jaws, so that their teeth 44 engage with the cork cylinders or rods in said grooves and press them against the strips 33 therein. In other words, before the feeding fingers move toward the knife and thereby feed the cork cylinders or rods a predetermined distance, depending upon the stroke of the bar 37, to the knife, the corresponding gripping jaws are raised, and when the feeding fingers move in the opposite direction, the corresponding gripping jaws are lowered into contact with the rods, so as to prevent them from sliding backward with the backwardly moving fingers. The table moves then in the opposite direction, the knife slicing disks from the rods in the group 25 of grooves. At the same time the anti-friction roller 53 of the lever 52 is lowered and rides near the end of the stroke of the table up the inclined face 55 of the cam 54, whereby the jaws associated with the group 25 of the grooves are forced into contact with the rods or cylinders therein, and the jaws cooperating with the group 24 of the grooves are raised. Before the end of the stroke is reached, the bar 37 is moved by the corresponding stop 41 in the corresponding direction, moving the feeding fingers associated with the group 25 of grooves away from the knife, and those coacting with the group 24 of grooves toward the knife, thus feeding the cork cylinders or rods in the manner above described toward the knife. The cycle of operation now described is then repeated.

It is to be observed that neither one of the tables has an idle stroke, the knives cutting at both strokes of the tables.

It should be observed that the inner face of the knife is, preferably, concave to prevent undue friction between the same and the cork cylinders or rods. The feed is entirely automatic. The strokes of the feeding fingers are easily adjusted, as appears from above, and thus the thickness of the cork disks conveniently predetermined.

What I claim is:—

1. In a machine for cutting disks from cylinders or rods, the combination with a rotary knife, of a table moving in parallel relation thereto provided with grooves parallel to the axis of the arbor of said knife, feeding fingers reciprocably arranged in said grooves for advancing the cork cylinders or rods in said grooves within the reach

of said knife, said feeding fingers being provided with longitudinal slots at diametrically opposite points thereof, strips on said table disposed in one set of the slots in said fingers, gripping jaws movably disposed on said table adapted to enter the other set of slots in said fingers, means for reciprocating said feeding fingers, and means for moving said gripping jaws into their corresponding slots and pressing thus the rods against said strips when said feeding fingers move away from the plane of said knife and for drawing the jaws out from said slots when said fingers move toward the plane of said knife.

2. In a machine for cutting disks from cylinders or rods, the combination with a bed plate, of a rotary knife thereon, a table on said bed plate moving in parallel relation to said knife provided with grooves parallel to the axis of the arbor of said knife, feeding fingers reciprocably arranged in said grooves for advancing the cylinders or rods in said grooves within the reach of said knife, gripping jaws movably arranged on said table and adapted to be brought in contact with the cylinders or rods in said grooves, a bar slidably disposed on said table having slots corresponding in number to the number of grooves therein, a lug on each feeding finger seated in a slot in said bar, stops on said bed plate for shifting said bar before the end of each stroke of said table, whereby said feeding fingers are reciprocated in said grooves, and means for rendering said gripping jaws operative when said feeding fingers move away from the plane of said knife and inoperative when moving toward the plane of said knife.

3. In a machine for cutting disks from cylinders or rods, the combination with a bed plate, of a rotary knife thereon, a table on said bed plate moving in parallel relation to said knife provided with grooves parallel to the axis of the arbor of said knife, feeding fingers reciprocably arranged in said grooves for advancing the cylinders or rods in said grooves within the reach of said knife, gripping jaws movably arranged on said table and adapted to be brought in contact with the cylinders or rods in said grooves, a bar slidably disposed on said table having slots corresponding in number to the number of grooves therein, a lug on each feeding finger seated in a slot in said bar, stops on said bed plate for shifting said bar before the end of each stroke of said table, whereby said feeding fingers are reciprocated in said grooves, an oscillatable shaft on said table, eccentrics on said shaft co-operating with said gripping jaws, and means on said table for oscillating said shaft, whereby said gripping jaws are rendered operative when said feeding fingers move away from the plane of said knife.

- and inoperative when moving toward the plane of said knife.
4. In a machine for cutting disks from cylinders or rods, the combination with a bed plate, of a rotary knife thereon, a table on said bed plate moving in parallel relation to said knife provided with grooves parallel to the axis of the arbor of said knife, feeding fingers reciprocably arranged 10 in said grooves for advancing the cylinders or rods in said grooves within the reach of said knife, said feeding fingers being provided with longitudinal slots at diametrically opposite points thereof, strips on said 15 table disposed in one set of the slots in said fingers, gripping jaws movably disposed on said table adapted to enter the other set of slots in said fingers, means for reciprocating said feeding fingers, an oscillatable 20 shaft on said table, eccentrics on said shaft coöperating with said gripping jaws, and means on said table for oscillating said shaft, whereby said gripping jaws are moved into their corresponding slots and 25 press thus the rods against said strips when said feeding fingers move away from the plane of said knife and draw said feeding fingers out of said slots when said fingers move toward the plane of said knife.
- 30 5. In a machine for cutting disks from cylinders or rods, the combination with a rotary knife, of a table moving in parallel relation thereto provided with one group of grooves near one of its ends and with an 35 other group of grooves near its other end, both groups running parallel to the axis of the arbor of said knife, feeding fingers reciprocably arranged upon said table for advancing the cylinders or rods in said grooves 40 within the reach of said knife, gripping jaws associated with said grooves, means for reciprocating said feeding fingers, said means causing the fingers associated with one group of grooves to move away from the 45 plane of said knife when the feeding fingers associated with the other group of grooves move toward the plane of said knife, and means for rendering said gripping 50 jaws operative when said feeding fingers move away from the plane of said
- knife and inoperative when moving toward the plane of said knife.
6. In a machine for cutting disks from cylinders or rods, the combination with a rotary knife, of a table moving in parallel relation thereto provided with one group of grooves near one of its ends and with another group of grooves near its other end, both groups running parallel to the axis of the arbor of said knife, tubular feeding 55 fingers reciprocably arranged in said grooves for advancing the cylinders or rods in said grooves within the reach of said knife, gripping jaws associated with said grooves, means for reciprocating said feeding fingers, 60 said means causing the fingers associated with one group of grooves to move away from the plane of said knife when the feeding fingers associated with the other group of grooves move toward the plane of said 65 knife, and means for rendering said gripping jaws operative when said feeding fingers move away from the plane of said knife and inoperative when moving toward the plane of said knife. 70
7. In a machine for cutting disks from cylinders or rods, the combination with a bed plate, of a rotary knife thereon, a table on said bed plate moving in parallel relation to said knife provided with grooves 75 parallel to the axis of the arbor of said knife, feeding fingers reciprocably arranged in said grooves for advancing the cylinders or rods in said grooves within the reach of said knife, a bar slidably disposed on said 80 table having slots corresponding in number to the number of grooves therein, a lug on each feeding finger seated in a slot in said bar, and stops on said bed plate for shifting said bar before the end of each 85 stroke of said table, whereby said feeding fingers are reciprocated in said grooves. 90

Signed at New York, in the county of New York, and State of New York, this 14th day of Dec., A. D. 1914.
